SASH MOUNTED AUTOMOBILE SIGNAL

Filed, May 18, 1929

2 Sheets-Sheet 2

UNITED STATES PATENT OFFICE

SAMUEL A. GAEDE, OF LOS ANGELES, CALIFORNIA

SASH-MOUNTED AUTOMOBILE SIGNAL

Application filed May 18, 1929. Serial No. 364,191.

This invention relates to traffic signals and especially to vehicle-mounted semaphores of the type established in my Patent No. 1,682,173, August 28, 1928.

5 The device provides a simple, substantial and highly effective means for mechanically accomplishing the conventional, driver's arm signal processes.

An improvement contained in the present 10 disclosure has for its purpose to provide a firm attachment of the device on the outer corners of channels of the sash for glass doors of automobiles so as to position the device near the top of the door.

15 An additional object is to provide a sure grip means to temporarily retain the arm in any of its selective signaling positions.

A desideratum is to provide means to facilitate neutral setting and retracting action 20 of the arm for ready position.

Other objects, advantages and features of construction and the combination, and its operation will be made manifest in the ensuing description of the herewith illustrative 25 embodiment; it being understood that modifications, variations and adaptations may be resorted to within the scope, spirit and principle of the invention as it is more directly claimed hereinafter.

30 An additional object is to provide an improved and reliable clamp for mounting the device.

Figure 1 is a perspective of the installed device with signal arm in "left" turn position.

Figure 2 is a longitudinal section of the device (broken away intermediately).

Figure 3 is an inside face view of the dismounted device (which is broken away).

40 Figure 4 is a vertical cross-section on line 4-4, of Fig. 3.

Figure 5 is a face view of the arm retainer.

Figure 6 is a face of the arm guide for selected signal positions.

45 Figure 7 is a diagram of an illumination circuit for the signal.

Figure 8 is a face view of one form of semaphor arm assembly.

50 Figure 9 is a plan of the arm assembly.

Figure 10 is a sectional view of the mounting plate and an attached switch structure.

Figure 11 is detail section of the switch.

The present apparatus is designed to be installed on the upper sash corners of an 55 automobile door D on the driver's side of the car.

It is found not desirable to mount the device by means set directly in the sash groove in which slides the glass W, and means are 60 provided to bear on the sash corners as will shortly be manifest.

The apparatus includes a semaphor 2 of hand, or other form, and its wrist part is secured to a stem 3 of a lever 4 which passes 65 through a ball 5 and has on its inner end a finger hook 6 provided with a pull cord 7.

The ball is frictionally clamped in a socket formed by an inner socket or shell 8 and an outer, main mounting plate 9 the pressure of 70 which parts on the ball is regulated by draw bolts 10. The plate 9 has a bearing boss 9^a 75 on its outer face.

Means are provided to guide the stem 4, 75 which projects inwardly through the shell 8 for manual operation, in a manner to position the hand 2 outward in any of three selective positions.

This means includes guideways S-L-R 80 formed in the hemispherical shell 8 and converging toward one side where there is a crotch C, Fig. 6 into which the lever 4 is pulled by the cord 7 to bring the hand flat back to ineffective or non-signal position, along the side of the mounting plate 9. The 85 guideways S and R are duplicate in form but of opposite curves to the top and bottom of the ball seat or shell, and the guideway L is straight across the seat. In order to properly track the lever 4 this has a neck 4^a, at 90 the ball, sharply bevelled at its front and rounded at its rear, Fig. 5.

When the driver intends to turn or to stop he simply applies a finger of the left hand to the retracted finger hook 6 and sharply 95 pulls it up or down, or straight back into the selective guiding track desired. The sharp neck of the lever 4 readily slips into the selected guideway and thereafter the flat sided neck hugs the guideway to its limit as 100

the hand 2 is thrown, non-turnably, into effective position, as in Fig. 1; the ball being held in place by the friction of the socket.

The pull cord leads back to a guide pulley 11, on plate 8, and when the hand 2 is to be retracted a pull on the cord swings the lever 4 back and brings horns 12 thereon hard up against a pair of rigid stop or abutment lugs 13 which are disposed one above the other at opposite sides of the center line of the crotch C so as to automatically turn the neck 4^a into a neutral or "ready" position for next action.

A feature of this neutralizing device resides in providing the horns 12 with re-entrant cam faces 12^a which facilitate the tilting of the lever 4 to ready position as soon as one horn comes to engagement with its respective lug 13.

The socket parts 8—9 and the signal hand 2 may be installed in various suitable locations, and in the present case the mounting means includes an adjustable jamb wing 15 having a corner or stile hook 16 and an opposite stile hook 17 on the main plate.

The swing 15 is slidably mounted on the inside face of the plate 9 and has a clamp bolt 19 sliding in slots 20 in the plate 9 and in a clamp leaf 18 which overlaps the near end of the wing 15 and is fixed on the plate 9.

Means for relatively adjusting the wing on the plate 9 consists of a cam wedge 21 pivoted flat on the leaf 18 at pivot 22 and having a cam wall slot 23 in which the bolt 19 is fitted. The head of the bolt has a vice-bar 19^a for leverage whereby to firmly set the bolt 18 when the wing 15 has been thrust outward to expanded position and the hooks 16—17 jambed against the corners C of the door sash. The expanding cam wedge 21 has a suitable purchase lever 21^a to facilitate tight adjustment prior to setting the clamping bolt 19.

In order to securely detain the arm 2 in outward, signaling position a detaining device is combined with the ball shell 8 and consists of a yoke piece 30 secured to the shell and having stout arms 31—32 spaced apart and having converged lips 33 to pinch on the neck 4^a of the lever 4 as this is pulled between the arms 31—32 and is thus frictionally steadied. If the neck 4^a is pulled up or down it passes against one of spurs 33^a on the ends of the arms 31—32 which press the neck to a steady position in the slots S—R; the spring arms acting in conjunction with the socket pressure, in the final portion of signal stroke.

It is desirable to provide a semaphor arm 2 which is effective and conspicuous for night service and for this purpose the arm is attached to a block 35 on the lever part 3 and which is provided with illuminating means as a bulb 36 which is connected in a circuit 37 primarily controlled by the head light switch 38 and includes a circuit closer blade

39 which is automatically actuated by means of the semaphor.

To effect such automatic action a slide 40 is slidably mounted in the plate 9 and has a cross-head 41 to be engaged by the lever 4 (of the arm 2) as this is pulled into any of the guideways in the shell 8. The slide 40 has a tail lug 42 which engages the switch blade 39 and this is pressed over against a yieldable contact 39^a to close the bulb circuit 75 as the arm 2 is thrown outward. On retraction of the arm the spring contacts 39—39^a press the slide 40 over and the circuit breaks again.

In Figs. 10 and 11 is shown a practical switch box 43 which is attached to the plate 9 to move with the car door D as it is opened and closed. The box has a removable cap 44 with lead wires of the circuit 37 to engage with spring contacts 45 of the circuit to the bulb 36.

When desired the cap 44 can be pulled to break the main wires from the parts of the circuit on the door.

The hand is shown as hollow and has apertured faces spaced from an intermediate reflecting partition 48 whose opposite faces are of different colors: the rear face is red and is illuminated by a red glass 49 while the front face is preferably green and is illuminated by a green glass 50; light passing from the source 36. This is but an example of semaphor arm and its illuminating means.

It is understood that the mount for the ball and socket device may be built into the door or car body.

The ends of the plates 9—15 are forced in between the packing felt P and the sash corners X and the hooks 16—17 are forced outwardly firmly against the corners. The top edges of the plates 9—15 are interheaded at 25 to obtain rigidity and smooth, guided sliding action of these parts.

What is claimed is:

1. A manually operated automobile signal device including a ball having a projecting semaphor arm and an oppositely projecting operating lever, a bearing socket for the ball having a series of lever guideways merging into a crotch, abutment means for tilting the lever to a ready position in the crotch, and horns on the lever having cam notches to engage said means.

2. A manually operated automobile signal device including a signal mounting plate and a wing plate slidably mounted on one end thereof for extension, a clamp leaf overlapping the wing and fixed to the plate, and means on said leaf for retracting or extending the wing.

3. A manually operated automobile signal device including a signal mounting plate and a wing plate slidably mounted on one end thereof for extension, a clamp leaf overlapping the wing and fixed to the plate, and

means on said leaf for retracting or extending the wing and including a clamp bolt and a rotative cam part engaging and reactive on the bolt.

5 4. A manually operated automobile signal device including a signal mounting plate having an extensible wing on one end, means to clamp the wing in adjusted position, and a cam member operative on the clamp means 10 to shift the wing prior to setting of the clamp.

15 5. A manually operated automobile signal device including a ball having a projecting hand member and an opposite operating lever, a selective guideway socket for the ball and lever, and a frictional detaining device gripping the lever at its extreme set positions.

20 6. A manually operated automobile signal device including a ball having a projecting hand member and an opposite operating lever, a selective guideway socket for the ball and lever, and a frictional detaining device gripping the lever at its extreme set positions; said detaining device including a yoked piece having resilient arms to engage the lever when this is full over.

25 7. A manually operated signal device including a main mounting plate and a wing plate slidably mounted on one end thereof; said plates each having an outward corner hook, and a clamp leaf overlapping the wing and having means to set the hooks against their supports.
